Atty.

UNITED STATES PATENT OFFICE.

EDWARD W. NEWELL, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

DRAFT-RIGGING.

1,245,260.

Specification of Letters Patent.

Patented Nov. 6, 1917.

Original application filed August 17, 1915, Serial No. 45,878. Divided and this application filed February 21, 1917. Serial No. 150,063.

To all whom it may concern:

Be it known that I, EDWARD W. NEWELL, a citizen of the United States, residing at Pittsburgh, in the county of Allegheny and State of Pennsylvania, have invented new and useful Improvements in Draft-Rigging, of which the following is a specification.

This invention relates to draft gears, and has for its principal object to provide means for equalizing the transmission of stresses from the draw-bar to the draft gear, the present application being a division of application, Serial No. 45,878, filed August 17, 1915.

In the accompanying drawing; Figure 1 is a vertical longitudinal section of the forward portion of a draft gear connected to a draw-bar and illustrating an application of my invention, and Fig. 2 a horizontal section of the construction shown in Fig. 1.

My invention may be applied in connection with any desired type of draft gear and in the drawing, the reference numeral 1 indicates a member of a draft gear adapted to engage the draw-bar 2, the draft gear being inclosed between the car center sills 3 in the usual manner.

Draft stresses are transmitted from the draw-bar 2 to the draft gear through a key 4 connected to the draw-bar 2 and extending through elongated slots 5 formed in the draft gear links 6.

In order to permit a lateral movement of the draw-bar 2 without disturbing the normal relation of the key 4 to the links 6 and thereby equalize the stresses transmitted to the draft gear, bushings 7 are interposed between the key 4 and the draw-bar 2.

The bushings 7 are adapted to fit over the front and rear portions of the key and are

provided with outer horizontal convex faces adapted to engage corresponding concave faces 8 formed in the draw-bar, as shown in Fig. 2 of the drawing. The rear end of the draw-bar 2 is provided with a horizontal convex face 9 adapted to engage a corresponding concave face formed on the draft gear member 1.

The above construction permits a lateral movement of the draw-bar relatively to the key so that the stresses transmitted from the draw-bar to the draft gear will exert substantially equal forces on opposite sides of the key.

The same action will be secured where a yoke is employed in place of the links 6, as will be evident.

Having now described my invention, what I claim as new and desire to secure by Letters Patent is:

1. The combination with a draw-bar and a draft gear, of a key for connecting the draw-bar to the draft gear and bushings for supporting the key in the draw-bar, said bushings having curved faces for engaging coöperating faces of the draw-bar to permit lateral movement of the draw-bar.

2. The combination with a draw-bar and a draft gear, of links connected to the draft gear, a key for connecting the links to the draw-bar, and bushings for supporting the key in the draw-bar, said bushings having curved bearings in the draw-bar and the draw-bar having a curved bearing on the draft gear to permit lateral movement of the draw-bar without moving the key.

In testimony whereof I have hereunto set my hand.

EDWARD W. NEWELL.
